Primary Examiner — Garth Rademaker*Assistant Examiner* — Llorellys Martinez-Rivera(74) *Attorney, Agent, or Firm* — Senniger Powers LLP**CLAIM**

The ornamental design for an LED night-light, as shown and described.

DESCRIPTION

FIG. 1 is a perspective view of an LED night-light showing the present invention;

FIG. 2 is a perspective view of the LED night-light of FIG. 1 with an optional lens shown in broken lines;

FIG. 3 is a front view of the LED night-light of FIG. 1;

FIG. 4 is a right side view of the LED night-light of FIG. 1;

FIG. 5 is a top plan view of the LED night-light of FIG. 1;

FIG. 6 is a rear view of the LED night-light of FIG. 1;

FIG. 7 is a bottom plan view of the LED night-light of FIG. 1; and,

FIG. 8 is a left side view of the LED night-light of FIG. 1. The text shown in broken lines in FIGS. 1, 2, and 3 is for illustrative purposes only and is not part of the claimed design.

The broken lines in FIGS. 1 through 8 illustrate portions of the LED night-light that form no part of the claimed design.

1 Claim, 8 Drawing Sheets(56)
